DIE HEAD

Charles A. Reimschissel, Waynesboro, Pa., assignor to Landis Machine Company, Waynesboro, Pa.

Application July 27, 1940, Serial No. 347,961

21 Claims. (Cl. 10—120.5)

This invention relates to a threading die used for cutting threads on bolts, rods, pipe or the like, and more particularly to an improved collapsible pull-off type head especially designed to use tangential chasers.

The present invention is an improvement over that disclosed in my U. S. Patent No. 2,082,758 granted June 1, 1937, which is likewise directed to a pull-off type die head, or in other words, a die head in which the collapsing or tripping of the head is actuated or produced by relative movement between separate shank and chaser bearing portions of the head, such relative movement causing the withdrawal of the chasers or thread cutters from the threaded work after the desired length of thread has been cut.

The invention of the present application is closely related to that of my co-pending application Serial No. 268,966, filed April 20, 1939, which latter application is directed to an improvement over that of my U. S. Patent No. 2,082,757 granted June 1, 1937. However, each of the two latter disclosures relates to yoke actuated die heads, whereas my present disclosure and that of my U. S. Patent No. 2,082,758 relate to pull-off type die heads.

In my present invention, I have utilized chaser holders of the same general type as those disclosed in copending applications Serial No. 249,324 (since issued as Patent No. 2,239,736, April 29, 1941) and Serial No. 249,325, (since issued as Patent No. 2,239,735, April 29, 1941) which applications I have filed jointly with E. M. Eigenbrode and which applications are based upon the disclosure of my United States Reissue Patent No. 20,930. Actually, my present chaser holders are somewhat modified, as compared with the ones in the above mentioned co-pending applications, in that the slide portions thereof are particularly adapted to be employed in a die head having an improved type of slideway bearing therefor. In view of the fact that my improved holder slide-die head slideway bearing arrangement in no way affects the primary function of the holders to retain and provide for adjustment of the chaser to the work, but merely assures having a better contact and a more satisfactory coaction between the holder slides and the die head proper, I, consequently, consider this phase of my disclosure to be an important integral part of my die head structure itself. Further, while a basically similar bearing arrangement is disclosed in my copending die head application Serial No. 268,966, I prefer the present construction because of certain inherent advantages thereof, namely: greater simplicity, greater adaptability, and lower cost of manufacture.

As can be gathered from the foregoing, my present pull-off die head represents an advance in design over that of my prior U. S. Patent No. 2,082,758, which largely parallels the advance in 5 yoke actuated die heads of the disclosure of my co-pending die head application Serial No. 268,966 over that of my U. S. Patent No. 2,082,757. By no means, however, is it to be construed that the difference between this disclosure and that of my co-pending die head application Serial No. 268,966 is merely one of applying essentially the same principles to differently functioning die heads; for, as later will be evident, the design of my new pull-off die head incorporates several 10 entirely novel features which are not disclosed in the aforementioned co-pending die head application. Likewise, the operation of pull-off and yoke actuated die heads is so basically different that the actual problems met in each instance 15 must be treated separately even though an attempt be made to base both designs upon the same fundamentals.

Consequently, it is an object of my invention to provide an improved type of pull-off die head 20 incorporating novel features which cause it to be simpler, more durable, and more accurate and efficient than any similar type die heads heretofore produced and yet having the features of considerable diametrical adjustability, positive locking against possible diametrical variations, and ease of collapsing normally required and expected of die heads of this type.

Another object of my invention is to provide a 25 pull-off type die head in which the parts that are subjected to wear are readily accessible so that they may easily be replaced or reconditioned. In this connection, while I have endeavored to produce a die head which is far more durable than any prior known die heads of its general type, it is obvious that no head structure can be designed so as to be entirely free from wear. Consequently, I have devised the head in a manner such that the maximum of components thereof may be made from material which can be hardened and may subsequently be ground without undue expense. Further, all of the major die head components are particularly adapted to permit the wearing surfaces thereof to be reconditioned with but a minimum of effort. Consequently, no serious loss of operating time is experienced, since the majority of repairs can be effected by the ultimate user.

While my present die head is primarily intended to be used as a pull-off type which is 30 manually reset to its cutting position, my construction also enables me to manually or mechanically trip the die head without relying upon

the pull-off action to effect the collapsing of the chasers; further, suitable camming means may be employed to reset the head automatically instead of by hand. Consequently, this feature of adaptability constitutes a further feature of my invention.

In addition to the above mentioned objectives, it has been my purpose to produce a pull-off type die head having the features of being self-sealed against the entrance of foreign matter, of being free from any possibility of entrapment of fluid which would tend to retard or otherwise interfere with the operation of the head, of utilizing a radial type latching mechanism having a circumferential bearing of relatively long life and which may be reconditioned with relative ease, and of utilizing improved type gibs adjustably mounted on the face of the head and having a sliding engagement with the chaser holder slides so that a precise fit may be maintained even after the die head has been in use for a long period of time—all of which features are, to a large degree, in accord with the basic design of the die head disclosed in my co-pending application Serial No. 268,966.

In addition to these general objectives, it has been my specific purpose to provide a pull-off type die head wherein the means for resetting the die head to threading position coacts with but is independent of the latch mechanism, having non-locking camming surfaces. This overcomes a disadvantage of the structure disclosed in my United States Patent 2,082,758 wherein the camming faces of the resetting means are adjacent to the latching faces of the latch, which arrangement eventually causes the latching faces to become worn and adversely affects their latching function. Further, the use of radially slideable latches permits having a faster camming action to trip the head as compared with a radially functioning latching arrangement of the type shown in my United States Patent 2,082,758. Thus, the tripping operation can be effected more quickly, and the die head may be made slightly shorter in length.

A further specific objective has been to provide a latch mechanism incorporating radially slideable latches adapted to be actuated in a dual manner, the latches having camming faces that are axially and peripherally inclined to effect radial displacements thereof by either axial or peripheral camming contact with the latch actuating member.

A further specific objective has been to provide a means for effecting the peripheral movement to reset the die head or to cause the peripheral camming of the latches, having integral therewith a means to limit its peripheral movement and thus minimizing the number of die head parts.

A further specific objective has been to provide a closing ring incorporating an uninterrupted annular latch coacting surface and an annular recess for the latch abutments, the recess being free of any head resetting functions which would require the precise machining thereof, whereby the structure is economical to produce and whereby the uninterrupted annular latch coacting surface may be reconditioned with greater ease than one of the type shown in my United States Patent 2,082,758.

Other objects and the nature and advantages of the invention will be apparent from the following description taken in conjunction with the accompanying drawings, wherein:

Fig. 1 is a face or end view of an improved die head in accordance with the present invention, two of the chaser holders being removed to reveal details of the chaser slide coacting slideways in the face of the head;

Fig. 2 is a longitudinal section on the line 2—2 of Fig. 1 with the parts of the head in closed or thread-cutting position;

Fig. 3 is a composite sectional view similar to that of Fig. 2 but showing one of the springs for opening the head at the termination of the threading operation, one of the retraction springs which normally prevents unintentional or premature head opening, and one of the camming means for effecting a resetting of the head to its thread-cutting position after it has been tripped;

Fig. 4 is a section on line 4—4 of Fig. 2 and showing details of the latching arrangement and of the hand opening feature;

Fig. 5 is a fragmentary view showing the outline of the latches employed;

Fig. 6 is a sectional view similar to that of Fig. 3 but showing the head parts in the open or collapsed position;

Fig. 7 is an offset sectional view on line 7—7 of Fig. 1 and showing the locking means used to prevent diametrical variations in the head setting during thread cutting; and

Fig. 8 is a fragmentary sectional view on line 8—8 of Fig. 1 and showing details of the slide and slideway bearing arrangement which I prefer to employ, the chaser holders being shown in elevation.

Referring specifically to Figs. 1 and 2, the die head of the present invention comprises a head body 20 having an extension 21 axially slidable within the coacting bore 22 of the shank member 23. Head body 20 also has integral therewith an enlarged head portion 24 adapted to carry and coact with chaser holders 41 and 42, and two others not shown; similarly, reduced portion 25 of shank 23 is adapted to be received within the coacting bore of some form of threading machine such as a turret lathe. In order to prevent relative rotation between the head body and the shank, the lugs 26 are formed integral with the latter and coact with suitable recesses 27 of head body 20. The foregoing comprises the means whereby the driving forces are transmitted to the cutter-carrying portion of the head.

In the enlarged forward portion 24 of the head body 20 are chaser holder slideways, 31, 32, 33 and 34 which coact, respectively, with slides on chaser holders 41, 42, and on two other similar chaser holders which have been removed to show the character of the bottom slide surfaces of slideways 33 and 34 (see Fig. 1). While the die head as herein shown utilizes four chaser holder assemblies, it is obvious that fewer or more such assemblies could be employed.

As heretofore noted, the chaser holders which I prefer to employ are in general of the types illustrated in copending applications Serial No. 249,324 and Serial No. 249,325. However, in the present instance, the slide portion of each of the holders is adapted to coact with an improved form of gibbing means in the face of the die head, the improved gibbing arrangement being closely related to that of my co-pending application Serial No. 268,966. Since all four of the present holders are basically similar, only the construction of the assembly incorporating holder 41 will be discussed. Chaser holder 41 has therein a recess 45 adapted to receive the tangential chaser 50, and it further incorporates another recess 47

in which is located the chaser clamp 60. Clamp 60 coacts with clamping screw 65 to clamp the chaser 50 to holder 41; further, adjustment serrations 51 on chaser 50, and 61 on clamp 60 are provided to interlock these two members so that they may be adjusted as a unit with respect to the holder in the manner disclosed in the said co-pending applications Serial No. 249,324 and Serial No. 249,325. The adjustment screw 70, located in an integral lug 48 of holder 41, is provided to effect longitudinal positioning of the chaser and clamp unit with respect to the holder. Since this much of my present disclosure is entirely in accord with the disclosures of co-pending applications Serial No. 249,324 and Serial No. 249,325, it is evident that my present invention is not concerned with any new form of chaser adjustment nor with any novel chaser-holder functions. However, I do disclose an improved means for retaining the chaser slides within the die head, which arrangement will now be described.

The present holder assembly utilizes an improved type of holder slide die head gib arrangement, the outline of which can best be seen in Fig. 8. The base surface 81 of the slide portion of the holder 41 is in intimate contact with slideway surface 82 of the respective slideway; and holder slide surfaces 84 and 85 are likewise in similar contact with slideway surfaces 86 and 87, respectively. These latter mentioned surfaces are preferably normal to the first mentioned surfaces. To retain the holder slide within its slideway, the gib 91 is located within a recess 96 in the forward portion 24 of die head body 20 and is so designed that the forward portion 100 thereof has its bottom surface 101 in intimate contact with holder slide surface 106. Similar gibs 92, 93, and 94 are provided for the slides of the respective other holder assemblies employed in this die head; likewise, similar gib recesses 87, 88 and 89 are provided to coact with these respective gibs. These gib recesses are so proportioned that the top surface of each of the respective gibs resting therein does not extend beyond the face of the die head even when several thicknesses of shim stock (not shown) are inserted between the gib and the bottom of its respective die head recess. Thus, in addition to providing a means for taking up the wear to which the bottom surfaces of the gibs are subjected, this arrangement assures having a flush die head face surface 110, which preferably is offset by a slight clearance (not visible) from the under surfaces 111 of each of the holders so that they are supported entirely by the respective slideways. Each of the gibs is fastened to the die head by fillister head screws 115 and is so designed that the gib surface 120 does not bear against the holder slide. The slight clearance which does exist between these surfaces is not visible due to the scale of the drawings.

As has previously been stated, my present holder slide gibbing arrangement is basically similar to that disclosed in co-pending die head application Serial No. 268,966; consequently, it incorporates the many advantages thereof over ones such as those disclosed in my U. S. Patent No. 1,951,290 and in co-pending applications Serial No. 249,324 and Serial No. 249,325. It should be noted that the L-shaped slide is much easier to machine accurately than the dovetail type and that inherently it is better adapted to withstand longitudinal cutting thrusts. The use of adjustable gibs makes it possible to hold the chaser

holder in intimate contact with the bottom of its slideway, which wear compensating arrangement assures accurate chaser holder retaining for a much longer period of time than was possible heretofore. Wear will naturally tend to be confined to the under surface 101 of the gib, since it is only during the initial thread starting period that the holders are being forced against the face of the die head—the subsequent nut action of the tangential chasers being of sufficient magnitude to tend to pull the holders away from the die head face. Since it is relatively inexpensive to recondition this gib surface, the present arrangement is superior to those employing dovetails regardless of whether they are gibbed or not. Likewise, since my present arrangement dispenses with the T-shaped gibs utilized in copending application S. N. 268,966, it is possible for me to apply it to small sizes of die heads which have insufficient face surface area to receive these larger and more complicated type gibs, which are inherently more expensive to produce and which are in no way superior to my present gibs.

Each of the holders is provided with a camming means 125, located within a slot 126 thereof. These camming means are adapted to cooperate with coacting means on one of the respective prongs 127, which form integral parts of the closing ring 130 that is slidably mounted on the die head body 20. Forward movement of the closing ring 130 causes the chaser holders to be displaced radially inward by the camming contact provided by the respective closing ring prongs. Likewise, rearward movement of this ring causes the chaser holders to be displaced radially outward and thereby releases the chasers from the work. The manner in which the closing ring cooperates with the head body to so actuate the chaser holders is more fully described in my said prior die head disclosures of U. S. Patents No. 2,082,757 and No. 2,082,758.

Referring more particularly to Figs. 2, 3, 5 and 6, opening springs 135 are disposed in bores provided in the forward portion of the head body 20 and in the closing ring 130. When the die head is in its closed or threading position, the combined force of these springs serves to press end surface 131 of closing ring 130 against the bottom surfaces 140 of latch members 145. This spring force, in turn, is transmitted directly to the locking ring 150, each latch member having a surface 141 bearing directly against the said locking ring 150. To oppose this rearward force acting on locking ring 150, an adjusting ring 160 is adjustably connected to the head body 20 by virtue of the engagement of its threaded section 162 with the threaded portion 163 of said head body and incorporates an overhanging flange 161 which coacts with a shoulder 151 on locking ring 150. Thus, these parts form a closed unit which henceforth will be referred to as the front or pull-off unit of the die head.

The locking means 165 for the diametrical setting is utilized to prevent undesired rotation of adjusting ring 160 with respect to head body 20. This means comprises a member 166 which is attached to head body 20 by screw 167 and which carries the thumb-screw 168 that contacts the exterior peripheral surface of ring 160 and exerts a frictional locking effect sufficient to prevent the ring from rotating (see Fig. 7). In addition to serving as means to adjustably, yet positively, determine the axial displacement between the head body and the closing ring, which na-

turally establishes the radial position or cutting diameter of the chaser holders, the adjusting ring 160 serves as an effective seal against the entrance of foreign matter into the interior of this front unit of the die head.

The rear unit of my die head is comprised of the shank member 23 and the retaining ring 170 which is adapted to rotate with respect to the said shank and which normally is in contact with the rear face 177 of the annular shoulder 175 thereof. The locking ring 150 incorporates a plurality of bores containing pull-back springs such as the spring 180. The force of the spring 180 acts against the head 186 of the pin 185, which pin is adapted to be fastened to the retaining ring 170. The combined force of the pull-back springs acts to press the counterbored surface 132 of locking ring 150 against the front face 176 of annular shoulder 175 and to press the retaining ring 170 against the rear face 177 thereof. Thus, these pull-back springs comprise a resilient connecting means which normally holds the front and rear units of the die head together in firm contact.

If a certain size of thread is desired to be cut and the die head is not set for that particular size, it is merely necessary to loosen the thumbscrew 168 and then rotate the adjusting ring 160, by placing a suitable wrench in the recessed socket 164 thereof, until the desired diametrical setting of the holders has been effected by having the proper axial displacement between the closing ring 130 and the head body 20. It should be remembered that the closing ring 130 is forced to move as far rearward as the flange 161 of adjusting ring 160 will permit it to go, for the opening springs 135 are constantly urging it rearwardly with respect to the head body 20. Thumbscrew 168 is then tightened so that no accidental relative rotation can occur between the adjusting ring and the head body.

As the chasers engage the work, the initial rearward axial thrust on the front unit of the die head is absorbed by the shoulder 175 of shank 23, for the locking ring 150 bears against the front face 176 thereof. After the first few threads have been formed, the chasers can serve to act as their own leadscrew, in which case, the front unit no longer presses against the shoulder 175 but is in equilibrium with the rear unit, being restrained from moving forwardly with respect thereto by the force of the pull-back springs 180. When the desired thread length has been cut, the relative axial movement between the die head and the work is interrupted by some form of stop (not shown). However, since the chasers still are engaged with the work and since the relative rotation therebetween has not been interrupted, the front unit of the die head starts to pull away or separate from the rear unit thereof, meanwhile compressing the pull-back springs 180.

As the above mentioned pull-off action commences, the latch members 145 are pressed radially outward, due to the camming contact between their inclined surfaces 142 and the peripheral latch surfaces 190 of shank member 23, meanwhile compressing the latch springs 195 which are constantly urging the latches inwardly. This camming action continues until the bottom surfaces 140 of latch members 145 lose contact with the end surface 131 of closing ring 130 and are aligned with the annular recess 133 thereof. The opening springs 135 now force the closing ring 130 rearwardly until its end surface 131 is in contact with the front surface 153 75

of locking ring 150. This relative axial movement between the head body 20 and the closing ring 130 results in causing the chasers to be moved radially outwardly and thereby to lose their contact with the work. Consequently, the pull-back springs 180 draw the front unit of the die head back into contact with the shoulder 175 of shank 23. The die head now is in its tripped or collapsed position (see Fig. 6).

To reset the die head to its original thread-cutting position, it is necessary to axially advance the closing ring 130 forwardly away from its contact with surface 153 of locking ring 150 so that the latch members 145 can again have their bottom surfaces 140 in contact with end surface 131 of said closing ring 130. For this purpose, there is provided the cam pin 200 carried by the closing ring 130 and whose concave-shaped head is adapted to fit into the countersunk recess 205 of the locking ring 150. By rotating the locking ring 150 relative to the closing ring 130, the camming contact between pin 200 and the coating recess 205 serves to move the closing ring forwardly until the latch springs 195 again are free to move the latches 145 radially inwardly to their initial positions. Two of these pins and recesses are used to ensure easy operation.

When the head is in locked condition, the latches 145 prevent the closing ring 130 from moving rearwardly (see Fig. 2). While Fig. 3 may be interpreted to show the pin 200 and socket 205 in contact at a rear point so as to prevent counter-clockwise rotation of the locking ring 150, as seems especially the case and purpose in Fig. 4, during the resetting operation there is an excessive amount of counter-clockwise rotation imparted to the locking ring 150 to be assured that the closing ring 130 has travelled sufficiently forwardly to assure having the latches 145 move inwardly to locked position; consequently, the necessary clockwise rotation of the locking ring 150 to permit closing ring surface 131 to abut the latches will be limited finally only by the camming resistance between latch surface 142 and surface 190 of the shank. Excessive clockwise rotation of locking ring 150 will open the head, but before any opening action occurs, the pin 200 and socket 205 will have lost all contact. Therefore, the pin 200 and socket 205 need not necessarily be in contact when the head is in cutting condition, in fact, a slight clearance therebetween is more generally the case than the contact shown in Fig. 4. Consequently, when the head is in locked condition, the pin 200 and socket 205 serve no useful purpose.

On the other hand, when the head is opened, the pin 200 and socket 205 are in full contact (see Fig. 6). These then serve as a spring pressed detent and prevent relative rotation of the closing ring 130 and locking ring 150. At no time does the end of pin 200 rest on the surface 153 of locking ring 150. Consequently, in open position, the pin 200 and socket 205 merely await manual counter-clockwise rotation of locking ring 150 to effect their only function: that of separating the rings 130 and 150 to permit locking of the head. So, these elements are correctly termed non-locking ones in that they do not lock the head in threading position.

For the purpose of rotating the said locking ring 150, I have provided a handle 210 which is threaded into said ring 150 and whose reduced

end 211 coacts with a keyway 212 formed in the shank member 23. The keyway 212 extends a sufficient peripheral distance so as not to interfere with the rotation of the locking ring 150; however, it does limit the range of rotation thereof. It is evident that a cam (not shown) could be employed to reset the die head automatically by effecting the proper rotation of the handle 210.

If it should be desired to trip the die head manually instead of relying on the pull-off action, to facilitate such tripping, I have provided the latch members 145 with camming surfaces 142 which are designed to coact with the peripheral latch surfaces 190 of shank 23 and which also are further inclined therewith in a second plane so that relative rotation between the locking ring and the shank results in a substantial radially outward movement of the said latches 145 (see Fig. 4). Thus, it is not necessary to attempt to manually open the die head solely by forcing the front unit thereof forwardly, for a minor rotation of the handle 210 effects a major outward displacement of the latches and very little additional effort is required to pull the front unit of the head sufficiently forward to effect a collapsing of the chasers. Again, it is clearly evident that an auxiliary cam (not shown) could be used to actuate the handle instead of manually so doing. As can be appreciated, this constitutes an important safety feature.

From the foregoing description of my die head, it will be evident that I have accomplished my original objectives, and have produced a pull-off type die head whose features are comparable to those of the yoke actuated type die head disclosed in my co-pending application Serial No. 268,966 and which has additional important features only inherent therein.

It will be obvious to those skilled in the art that various changes may be made in this device without departing from the spirit of the invention and therefore the invention is not limited to what is shown in the drawings and described in the specification but only as indicated in the appended claims.

What is claimed is:

1. A two unit head for mounting a thread-cutting tool comprising a front unit including a body member, a closing ring, an adjusting ring, and a locking ring, and a rear unit including a shank member and a retaining ring; said closing ring and said locking ring having mutually coacting non-locking camming means of a configuration adapted to effect relative axial displacement thereof.

2. A two unit head for mounting a thread-cutting tool comprising a front unit including a body member, a closing ring, an adjusting ring, and a locking ring; and a rear unit including a shank member and a retaining ring; said shank member having latch actuating surfaces and said locking ring having radially slideable therein a plurality of latch members having complementary camming surfaces adapted to be actuated by virtue of their camming contact with respective latch actuating surfaces formed on said shank member.

3. A head for mounting a thread-cutting tool comprising a closing ring and a locking ring axially displaceable one relative to the other, and mutually coacting non-locking camming means disposed in said rings and of a configuration for

producing relative axial displacement of said rings.

4. A head for mounting a thread-cutting tool having a shank member provided with latch actuating surfaces, a locking ring, one or more radially slideable latch members mounted in said locking ring, said latch members being provided with complementary camming surfaces adapted to be actuated by camming contact with said respective latch actuating surfaces.

5. A two unit head for mounting a thread-cutting tool comprising a front unit including a body member, a closing ring, an adjusting ring, and a locking ring, and a rear unit including a shank member and a retaining ring; said shank member having latch activating surfaces thereon, a plurality of mutually coacting non-locking camming means located in said closing and locking rings and adapted to effect axial displacement thereof; radially slideable latch members mounted in said locking ring and adapted to be actuated by virtue of their camming contact with said respective latch actuating surfaces formed on said shank member.

6. A head for mounting a thread-cutting tool as is set forth in claim 1; said mutually coacting non-locking camming means comprising a cone-headed pin located in one of said rings and cooperating with a countersunk camming surface formed in the other of said rings.

7. A head for mounting a thread-cutting tool as is set forth in claim 5; said mutually coacting non-locking camming means comprising a plurality of cone-headed pins located in said closing ring and having respective camming contacts with a plurality of countersunk camming surfaces formed in said locking ring; means for resiliently pressing said radially slideable latch members into engagement with said latch actuating surfaces of said shank member.

8. A head for mounting a thread-cutting tool including a locking ring, radially slideable latch members mounted in said locking ring and having camming surfaces coacting with cooperating camming surfaces on another member of the head, the camming contacts being both inclined with respect to and spiralling away from the longitudinal axis of the head whereby said latch members are actuated by both relative axial displacement and relative rotational displacement between said locking ring and said other member of the head.

9. In a two unit head for mounting a thread-cutting tool, radially slideable latch members mounted in one of the two units of the head, latch actuating surfaces in the other unit of the head, said latch members each having an inclined spiral camming contact with said latch actuating surfaces, whereby either relative axial displacement or relative rotational displacement between said two units of the head will actuate said latches radially.

10. A die head having a shank member provided with a circumferential keyway, a closing ring, a locking ring, radially slideable latch members carried by said locking means, said closing ring and said locking ring having mutually coacting non-locking camming means for axially displacing said radially slideable latch members relative to said closing means, means for limiting the total permissible rotation of said locking ring relative to said shank member, said means comprising a handle mounted in said locking ring and having limited peripheral movement within the confines of said circumferential keyway.

11. A two unit head for mounting a thread-cutting tool as is set forth in claim 5; said camming contact of said latch members and associated parts being so constructed and arranged as to be extremely quick acting and independent of any head resetting functions, whereby the reduction in the required relative axial tripping movement of the front and rear units of the head facilitates having a die head of lesser total length.

12. A head for mounting a thread-cutting tool as is set forth in claim 5; said closing ring of said assembly having an uninterrupted annular latch coating surface which forms a locking seat for the latching surfaces of said radially slidable latch members.

13. A head for mounting a thread-cutting tool as set forth in claim 5; said closing ring of said assembly having an uninterrupted annular latch coating surface to form a locking seat for the latching surfaces of said radially slidable latch members and further having an annular recess concentric therewith and adapted to receive the latch abutments of said latch members as the head is tripped; said annular recess of said closing ring being independent of any head resetting functions.

14. A die head comprising a body member, a shank member, a plurality of chaser holders slidably mounted on one end of said body member, tangential chasers mounted on said holders, closing and locking rings mounted on said body member, and an adjusting ring connected to the body member and extending over said closing ring and connected to said locking ring with a bearing engagement to hold the said rings assembled on the body member, said locking ring having radially slidable latch members mounted therein and adapted to be actuated by virtue of their camming contact with respective latch actuating surfaces formed on said shank member which is provided to drive said head body.

15. A die head comprising a body member with an enlarged head face, a plurality of chaser holders having tangential chasers thereon, means mounting said chaser holders to slide radially on said head face, said enlarged head face having a rearwardly extending peripheral flange, a closing ring extending into said peripheral flange and having prongs thereon extending through the head face and engaging said chaser holders so as to move them radially in and out on said head face, springs within said enlarged head face to force said closing ring rearwardly with respect to the chasers, a locking ring behind said closing ring, cone-headed pins located in one of said rings and coating with countersunk camming surfaces provided in the other of said rings to effect forward movement of the said closing ring, an adjusting ring extending from said peripheral flange over said closing and locking rings and having bearing connection with the locking ring, and a threaded connection between said adjusting ring and said peripheral flange of the body member to form a joint therewith and provide means for changing the radial position of the chaser holders on the die head face for positioning the chasers to cut threads of any desired diameter.

16. A die head comprising a body member having chaser holders and tangential chasers slidably mounted thereon, a closing ring mounted for axial movement on the body member and cooperating with the chaser holders to move them radially in and out on the body member, a lock-

ing ring movably cooperating with said closing ring for operating the closing ring to thread cutting locked position and permitting it to move to unlocked or released position to open the chaser holders and chasers and further cooperating with a shank member provided to drive said body member in that a plurality of radially slidable latch members are mounted therein and are adapted to be actuated by having camming contact with respective latch actuating surfaces formed on said shank member, opening springs positioned between the body member and closing ring to provide means for forcing the closing ring to its open or release position when the locking ring has been moved to a position permitting the chasers to open, and an adjusting ring connecting the body member and locking ring to hold the die head members assembled and permit adjustment to vary the diameter of the threads cut by the chasers.

17. A die head comprising a body member having radially movable tangential chasers, an axially movable member for moving the chasers radially into and out of thread cutting positions, a locking member cooperating therewith for effecting the movement of the chasers to a locked thread cutting position, spring means between said chaser moving member and the die head body member for effecting a retracting movement of the chasers to released or non-thread cutting position, an adjusting ring connecting said body member with said locking member and enclosing said chaser moving means, a supporting member upon which said body member is axially movable, yieldable connecting means between said locking member and said supporting member retaining said body member thereon and permitting a forward movement thereof, and radially slidable latching means mounted in said locking member and having camming surfaces contacting with latch actuating surfaces on said supporting member to effect a movement of the chasers to released position upon such forward movement of the head body.

18. A die head comprising a body member having radially movable tangential chasers and chaser moving members, a rear supporting unit therefor comprising a shank with a collar thereon inward of its front end, means for mounting a die head so as to move axially on said shank forwardly of said collar, a retaining ring on said shank in cooperative engagement with said collar, yieldable connecting means between said retaining ring and said die head members permitting the die head to move forwardly on the front end of the shank member, and means co-operating with the chaser moving members to effect an opening of the chasers when the body portion of the die head moves forwardly on said supporting member, said means comprising radially slid able latch members having camming surfaces contacting with latch actuating surfaces formed on said shank.

19. In a thread cutting die head a front unit, a rear unit, thread cutting means on said front unit movable between closed and open positions, means for locking said thread cutting means in closed cutting position, means connecting said front and rear units to provide a positive drive therebetween, and cooperating retaining ring and stop means on said front and rear units limiting the movement of the front unit forwardly of said rear unit, said connecting means permitting the front unit to move forwardly of the rear unit without disturbing said positive drive or

the locking action of the cutters, said means for locking said thread cutting means comprising radially slidible spring pressed latches located in said front unit and having axial and rotative camming contact with coacting latch actuating surfaces located in said rear unit of said die head.

20. A head assembly for mounting a thread-cutting tool having a shank member provided with a circumferential keyway, a closing ring, a locking ring, radially slidible latch members carried by said locking ring and coacting with latch camming surfaces on said shank to open said head, said closing ring and said locking ring having mutually coacting non-locking camming

means for axially displacing said closing ring relative to said locking ring, means for limiting the total permissible rotation of said locking ring relative to said shank member, said limiting means including a handle mounted in said locking ring and having limited peripheral movement within the confines of said circumferential keyway.

21. The combination set forth in claim 20, wherein said radially slidible latch members are adapted to coact with said latch camming surfaces of said shank and with said limiting means to restrain said locking ring from appreciable clockwise or counter-clockwise rotation.

CHARLES A. REIMSCHISSEL.
